Dec. 204

Wm Savery joint inventor with and Ass^{ee} of Jas. H. Conklin.
City of New York, N. Y. Letters Patent No 204, dated Nov 21. 1848.

The Schedule referred to in these Letters Patent and
making part of the same.

To all whom it may concern: Be it known that William Savery and James H. Conklin of the City, County, and State of New York have invented or produced a new and ornamental design for a Cylindrical Coal Stove, with several ornamental figures for the said stove, combined in one; - and we do hereby declare that the following is a full and exact description of the same, reference being had to the annexed drawings, making part of this specification.

Drawing No 3. represents a front view of the whole stove: D being the hearth plate; B being one of the sides of the base; C being the cap of the base and bottom of the cylinder; E being the cylinder; A being the top or cap of the cylinder, and F the opening in the cap: - Figure 1 of Drawing No 1. is a section of the ornament or cap C and figure 2 is a section of the ornament of hearth plate D. Figure No 3 of Drawing No 2 is a section of the ornament for the top A and Figure 4 is a section of the side of the base B.

What we claim as original and desire to secure by Letters Patent is the arrangement and combination of the several original original ornamental figures upon this particular stove as herein described, and represented by the annexed drawings
